SEPARABLE LINK BRACELET OR CHAIN

Filed Sept. 25, 1925

FIG. 2.

FIG. 4.

Inventor

Frederick W. Nittel
By Joseph A. Miller

Attorney

Patented Feb. 23, 1926.

UNITED STATES PATENT OFFICE.

FREDERICK W. NITTEL, OF ATTLEBORO FALLS, MASSACHUSETTS, ASSIGNOR TO M S COMPANY, OF ATTLEBORO, MASSACHUSETTS.

SEPARABLE-LINK BRACELET OR CHAIN.

Application filed September 25, 1925. Serial No. 58,595.

To all whom it may concern:

Be it known that I, FREDERICK W. NITTEL, a citizen of the United States, residing at Attleboro Falls, in the county of Bristol and

5 State of Massachusetts, have invented new and useful Improvements in Separable-Link Bracelets or Chains, of which the following is a specification.

This invention relates to certain new and 10 useful improvements in separable link bracelets or chains and it has for its object to provide an improved link construction and assembly in which adjacent link elements cooperate with each other to form a simple 15 and durable bracelet chain in which the links are locked in properly spaced relation.

The invention consists in the provision of two series of links, the links of one series serving to space adjacent links of the other 20 series and also to secure the latter links in connected relation with those links of the first series.

In the drawings:—

Figure 1 is a view depicting, in fragment, 25 a chain such as may be used for bracelets and the like;

Figure 2 is a longitudinal, sectional view thereof on line 2—2 of Fig. 1; and

Figures 3 and 4 are perspective views of 30 the two forms of links of which the chain is constructed.

Referring more in detail to the accompanying drawing, the numeral 1 designates a box-like link which is herein depicted as 35 being formed from a single strip of sheet metal folded at its transverse center to form a box-like body having sides 2 and with its free ends secured together by a tongue 3, on one end, clinched into a slot formed in the end wall 4, on the opposite end, as shown in Fig. 4. The sides 2 are cut away for 40 nearly their entire length, as indicated at 5, for receiving the side arms of the spring actuated links.

45 Each spring actuated link is substantially of rectangular U-shape, the base 6 sliding between the top and bottom walls of the box link 1 and the side arms 7 being guided through end openings 8 formed in the end wall 4. The free ends 9 of the arms 7 are

turned inwardly toward each other and the extremity of each inturned end 9 is directed toward the base 6 as at 10 thereby forming a stirrup.

The box link has its top and integral end 55 walls divided by parallel slots 11 which extend into the bottom wall, as shown in Fig. 2, which slots divide the end wall into a plurality of sections, the outer of which are designed to seat in the stirrups at the free 60 ends of the arms 7 while the intermediate section 12 lies between the spaced extremities 10 extend through the end wall slots 11 of one box link into normal engagement with the end wall 4 of the adjacent box link and 65 serve as spacing lugs between the two box links, as seen in Figure 1, whereby the former box link will have free pivotal movement about the inturned ends 9 as pintles. The base 6 of the spring actuated U-link is 70 centered in its box link by lugs 13 pressed up from the base and operating in the slots, 11.

A coil spring 14 is housed within the box link between the side-closing side arms 7, said spring being compressed between the 75 end wall 4 and the base 6 for urging the latter toward the opposite end wall and thereby tending to contract the bracelet or chain to its normal size.

The links are readily separated by distending the companion box and U-links and then, 80 by holding the U-link distended, the adjacent box link is swung laterally approximately ninety degrees when the slotted end wall is moved edgewise out between the spacing lugs 10. To assemble the links, the slotted end is threaded between the lugs 10 and then the box link is swung around into alignment with the U-link thereby bringing the end wall over the pintle portions 9. 85

Having thus described my invention what I claim as new and desire to secure by Letters Patent is:—

1. A separable link construction comprising a plurality of box links each having one 95 end wall slotted and the opposite end wall formed with spaced guide openings, a plurality of connecting U-links having their bases slidable between the top and bottom walls of the respective box links and their 100

- side arms slidable through the end wall guide openings, the free ends of the side arms being extended inwardly into the slotted end of an adjacent box link, and means on the inturned ends of the side arms extending through the slot of the slotted end walls for engaging the second named walls of adjacent box links for spacing the respective box links.
10. 2. A separable link construction comprising a plurality of box links each having one end wall slotted and the opposite end wall formed with spaced guide openings, a plurality of connecting U-links having their bases slidable between the top and bottom walls of the respective box links and their side arms slidable through the end wall guide openings, the free ends of the side arms being extended inwardly into the slotted end of an adjacent box link, said inturned ends having their extremities directed toward the bases to provide spacing lugs for extending through the slots of the slotted ends and into engagement with the second mentioned ends of the box links for spacing from the latter the inturned ends whereby the latter serve as pintles about which the connected box links may pivot.
15. 3. A separable link construction comprising a plurality of box links each having one end wall divided by a pair of slots, which slots extend into the top and bottom walls of the box links, a plurality of connecting links of substantially U-shape, each connecting link having its base slidable between the top and bottom walls of a respective box link and having its side arms guided through the opposite end wall of the latter, the free ends of the arms being inturned into engagement with the slotted end wall of the adjacent box link.
20. 4. A separable link construction comprising a plurality of box links each having one end wall divided by a pair of slots, which slots extend into the top and bottom walls of the box links, a plurality of connecting links of substantially U-shape, each connecting link having its base slidable between the top and bottom walls of a respective box link and having its side arms guided through the opposite end wall of the latter, the free ends of the arms being inturned into engagement with the slotted end wall of the adjacent box link, said inturned free ends extending between the top and bottom walls of said adjacent box link and interlocking in the adjacent slot of the latter.
25. 5. A separable link construction comprising a plurality of box links each having one end wall divided by a pair of slots, which slots extend into the top and bottom walls of the box links, a plurality of connecting links of substantially U-shape, each connecting link having its base slidable between the top and bottom walls of a respective box link and having its side arms guided through the opposite end wall of the latter, the free ends of the arms being inturned into engagement with the slotted end wall of the adjacent box link, said inturned free ends ex-

link and having its side arms guided through the opposite end wall of the latter, the free ends of the arms being inturned into engagement with the slotted end wall of the adjacent box link, said inturned free ends extending between the top and bottom walls of said adjacent box link and having their extremities outturned through the adjacent slots of the latter for spacing the same from the first named box link.

6. A separable link construction comprising a plurality of box links each having one end wall divided by a pair of slots, which slots extend into the top and bottom walls of the box links, a plurality of connecting links of substantially U-shape, each connecting link having its base slidable between the top and bottom walls of a respective box link and having its side arms guided through the opposite end wall of the latter, the free ends of the arms being inturned into engagement with the slotted end wall of the adjacent box link, said inturned free ends extending between the top and bottom walls of said adjacent box link and having their extremities outturned through the adjacent slots of the latter for spacing the same from the first named box link, said outturned extremities being interposed by that portion of the slotted end wall of said adjacent link lying between the slots thereof.

7. A separable link construction comprising a plurality of box links each having one end wall divided by a pair of slots, which slots extend into the top and bottom walls of the box links, a plurality of connecting links of substantially U-shape, each connecting link having its base slidable between the top and bottom walls of a respective box link and having its side arms guided through the opposite end wall of the latter, the free ends of the arms being inturned into engagement with the slotted end wall of the adjacent box link, said inturned free ends extending between the top and bottom walls of said adjacent box link and having their extremities outturned through the adjacent slots of the latter for spacing the same from the first named box link, and means carried by the base of each U-link and operating in the slots of the respective box link for holding the former in position.

8. A separable link construction comprising a plurality of box links each having one end wall divided by a pair of slots, which slots extend into the top and bottom walls of the box links, a plurality of connecting links of substantially U-shape, each connecting link having its base slidable between the top and bottom walls of a respective box link and having its side arms guided through the opposite end wall of the latter, the free ends of the arms being inturned into engagement with the slotted end wall of the adjacent box link, said inturned free ends ex-

tending between the top and bottom walls of said adjacent box link and having their extremities outturned through the adjacent slots of the latter for spacing the same from the first named box link, and an expansion spring within each box link and compressed

posite end of the box link for urging the outturned extremities of the U-link into contact with the latter end of said box link. ¹⁰
In testimony whereof I have signed my name to this specification.

FREDERICK W. NITTEL.
